STEPHEN W. EATON, OF FARMINGTON, MAINE.

Letters Patent No. 64,958, dated May 21, 1867.

IMPROVEMENT IN SUPPORTS OR BEARINGS FOR FRICTION-ROLLERS.

The Schedule referred to in these Letters Patent and making part of the same.

TO ALL PERSONS TO WHOM THESE PRESENTS SHALL COME:

Be it known that I, STEPHEN W. EATON, of Farmington, in the county of Franklin, and State of Maine, have invented a new and useful Improvement in the Supports or Bearings of Friction-Rollers used for supporting the body of a railway carriage on the truck-frames thereof; and I do hereby declare the said invention to be fully described in the following specification, and represented in the accompanying drawings, of which—

Figure 1 is a top view, and

Figure 2 a side elevation of a roller and its supporting box.

The said box is to be fastened on the top part of the truck-frame, and with the roller resting on the upper surface of the base-plate of the box. The carriage body is to rest on the upper part of the periphery of the roller. The usual mode of supporting the roller is by journals projecting from it and sustained in cylindrical bearings formed in the cheek-pieces of the box or housing of the roller, in which case the weight of the carriage body and the friction-rollers is borne by the journals and their bearings. Under this state of things each of the rollers can have no other motion relatively to its housing or box than a rotary motion on and about the axis of the roller. It is found in practice that under this mode of supporting the roller it is very liable to become worn more or less flat on its periphery, whereby it will be prevented from revolving and performing its duty. The consequence of this is great danger of the car or carriage, while turning a curve, being thrown off or caused to leave the railway-track. My improvement not only obviates or greatly reduces all such danger, but it saves the roller from being so worn. It also saves the wheels and rails from much wear that would be experienced with the common roller bearing. It also effects a saving in the tractile force, or enables it to operate with greater effect in moving the carriage on a curve.

In carrying out my invention the journals *e e* of the roller *B* are arranged in long curved semicircular or other proper shaped recesses or notches *a a*, made in the cheek-pieces *b b* of the roller-supporter or box *A*, and the roller-bearings are not to rest on the bottoms of their recesses, but are to be off the same, the roller at its periphery being supported on the upper surface of the base-plate *c* of the box, and so that the roller may roll thereupon a short distance lengthwise of such plate, its movement either way being estopped by the journals of the roller bringing up against the shoulders of the elongated recesses or notches *a a*.

Thus the roller, by my improvement, can have a compound motion, that is to say, one of rotation on its axis, and one either forward or backward on the base-plate *c*. This enables the truck-frame to readily adjust itself to the curves of the rails of the track, as the roller will always revolve, and is not liable to become flattened on its periphery, as it is when cylindrical bearings for the journals are employed.

What, therefore, I claim as my invention, is—

The box *A*, constructed substantially as specified, viz, with the elongated recesses or notches *a a* to receive the journals of the roller *B*, and so made as to enable the roller to rest on the base-plate *c* of the box, and roll thereon a short distance in either direction from the middle of the plate, as described.

STEPHEN W. EATON.
